UNITED STATES PATENT OFFICE.

CHARLES L. RAGOT, OF NEW YORK, N. Y., ASSIGNOR TO RAGOT MOTOR CORPORATION,
A CORPORATION OF NEW YORK.

ROTARY ENGINE.

Application filed January 31, 1923. Serial No. 616,019.

To all whom it may concern:

Be it known that I, CHARLES L. RAGOT, a citizen of the United States, and resident of New York, in the county of New York and State of New York, have invented certain new and useful Improvements in Rotary Engines, of which the following is a specification.

This invention relates to rotary translating devices for fluid pressure mediums, in other words, rotary devices which may be actuated by the delivery of fluid thereto under pressure and serve as motors or prime movers, or may be actuated by outside power and impart pressure or motion to a fluid, thus serving as pumps or compressors.

More particularly my invention relates to the general type of construction illustrated in Patent 1,302,709 granted to myself and Louis F. Ragot on May 6th, 1919. In the construction there illustrated, two sets of radially disposed cylinders are arranged in parallel planes with an elliptical track therebetween, and power is obtained by utilizing the reaction caused by the side pressure of the piston against the cylinder wall due to the radial pressure exerted by the piston against the elliptical track at a point where the track recedes from the center. The resulting tangential pressure is translated into a rotary one by the relative bodily movement of the cylinders and track.

The main object of my present invention is to enable the pistons to be positively held closely adjacent to the outer ellipse when centrifugal force and fluid pressure are not sufficient to keep them in their outer limiting positions.

A further object is to secure this positive inward and outward movement with the minimum number of parts and in a simple and compact form, with the casings of the minimum size and the ellipse disposed between the rows of cylinders.

A further object is to provide an effective and rigid connection between the two sets of cylinders, and of such a character that it does not interfere with the track and the fluid distributing means.

A further object is to simplify the construction by forming at least one row of the cylinders integral with, or as a part of, the casing.

A further object is to provide rotary means inside of the casing for effecting the

rotation of the ellipse in relation to the stationary cylinders which are rigid with the casing.

A further object is to utilize the central distributor as a support for both track members and independent of the casing. 60

A further object is to provide a novel arrangement whereby the track members and the distributor are the only rotatable parts of the device inside of the stationary casing and which impart motion to or receive it from the shaft which extends to the exterior. 65

A further object is to provide a combined shaft and distributor which is mounted for rotation in the casing and carries all of the rotatable parts. 70

Other objects and advantages will be pointed out hereinafter, or will be apparent from a study of the specific construction 75 hereinafter described.

In the accompanying drawings:

Fig. 1 is a section at right angles to the axis of rotation of a device embodying my invention, said section being taken substantially on the line 1—1 of Fig. 2. 80

Fig. 2 is a longitudinal section taken on the line 2—2 of Fig. 1.

Fig. 3 shows another form which my invention may assume, and is a section at right angles to the axis of rotation thereof, said section being taken on the line 3—3 of Fig. 4, and 85

Fig. 4 is a longitudinal section taken on the line 4—4 of Fig. 3. 90

My improved device as illustrated in Figs. 1 and 2 includes a rotor and a stator, although with comparatively minor changes either of the two relatively rotatable parts may serve as the stator and the other as the 95 rotor.

The device includes two members 10 and 11 in the form of circular disks, and each presenting a plurality of radially disposed cylinders 12. The disks are preferably cast, 100 and the cylinders of each member are all formed integral. The member 10 may be provided with an outwardly extending flange 13 and serve as the end wall of a casing, the balance of the casing being 105 formed by a peripheral wall 14 rigidly connected to the flange 13, and a second end wall 15 connected to or integral with the peripheral wall. The cylinders of the two members are arranged in pairs, the two cyl- 110

inders of each pair being in the same radial plane. The two members 10 and 11 are rigidly secured together in spaced relationship by an annular row of connecting members arranged alternately with the cylinders. As shown in Fig. 2, the spacing is effected by bosses or hubs 17 on the two members and through each pair of abutting hubs is a connecting bolt 16.

10 Within the cylinders are pistons 18, the two pistons of each pair of cylinders being connected intermediate of their ends by a transverse member 19 which has a roller 20 intermediate of its ends and between the 15 two members 10 and 11. The connecting members 19 extend through longitudinal slots in the cylinders and the pistons are of such length as to prevent the escape of the motive fluid medium through said slots.

20 The rollers 20 engage with a non-circular track which in the form illustrated includes two members 21 and 22 presenting opposed parallel elliptical surfaces. The inwardly facing elliptical surface of the outer member 21 encircles the row of rollers 20 and connecting bolts 16, while the outwardly facing elliptical surface of the member 22 is inside of the row of rollers and connecting bolts. The proportions are such that 25 the inside diameter of the annular row of hubs or other spacing members 17 is greater than the major axis of the inner ellipse, and the outside diameter of the row of said spacing devices is less than the minor axis 30 of the outer ellipse. Thus there may be free relative rotation of the track and the cylinder members, without interference on the part of the connecting members 16. The rollers 20 are each of a diameter 35 slightly less than the radial spacing between the inner and outer ellipses, so that in normal operation they engage only with the outer ellipse and during stopping and starting they are held to the proper position by the inner ellipse and are prevented 40 from falling in toward the center or being rapidly shot out to the outer ellipse as the motive fluid is turned off or on. The major axis of the outer ellipse is preferably 45 smaller than the diameter of the circle described by the outer ends of the cylinder so that the casing is of the smallest possible 50 diameter.

Extending through the two members 10 55 and 11 is a central passage within which is mounted the motive fluid distributor 23 which is relatively rotatable in respect to the cylinder members 10 and 11. As shown, there is a bushing member 24 there between.

60 Each cylinder has a port 25 at its inner end, serving both as an inlet port and as an exhaust port for the cylinder. The distributor has suitable passages serving for the intake and exhaust of the motive fluid, 65 and each having ports for registering with

the ports 25. As shown, there are four of the passages 26, 27, 28 and 29, each having two ports, one for registering with the ports 25 of the cylinders of the member 10, and the other for registering with the ports 70 25 of the cylinders of the member 11. All of these ports of the four passages are in the two transverse planes of the ports 25, whereby each port communicates with the four passages 26, 27, 28 and 29 in succession. The two diametrically opposite passages 26 and 28 have ports communicating with an annular passage 30 in an annular boss or sleeve 31 on the casing, and the other two distributor passages 27 and 29 have 75 ports communicating with a second annular passage 32 in said boss or sleeve. These annular passages 30 and 32 have ports 33 and 34, one serving as an intake and the other as an exhaust for the motive fluid. Assuming the port 33 and passages 26 and 80 28 to be the intake, it will be apparent that the rotation of the distributor and the elliptical tracks in a clockwise direction, as viewed in Fig. 1, will cause fluid to be admitted to each cylinder as the minor axis of the elliptical track passes the port of that cylinder, and the delivery of motive fluid will continue until the major axis reaches or nearly reaches the port. Thereafter the exhaust passage will communicate with the port during the next quarter revolution. In Fig. 1 the parts are shown with the upper and lower cylinders on the minor axis, and with their ports closed. A rotation of the distributor clockwise will bring the port 25 of the upper cylinder into registry with the passage 27, and the piston will be forced outwardly during the next 85 quarter revolution.

As previously noted the elliptical track members and the distributor are rigidly connected for simultaneous rotation. As shown the inner track 22 is directly connected to or integral with the distributor, 90 while the outer track 21 is connected to a frame or spider including an end plate 35 secured to the distributor by bolts 36, or in any other suitable manner. This plate has a sleeve portion 37 extending across the outer ends of the cylinders in the member 11, and secured to the outer member 21 of the elliptical track.

The rotary parts which include the distributor and the two track members, may be 100 supported in any suitable manner in the casing. As shown there are provided ball bearings 38 and 39, and either or both ends of the distributor may be extended to form a shaft 40 from which power may be taken. The casing itself may be rigidly held 105 against rotation in any suitable manner, as for instance by means of a base 41. It will of course be apparent that if power is applied to the shaft 40 to positively turn the 110

rotor, the device may serve as a pump or compressor, while if motive fluid such as compressed air is delivered to the port 33 and permitted to exhaust through the port 34 the rotor will be caused to turn in one direction. By making the port 34 the intake, and the port 33 the exhaust, rotation in the opposite direction may be secured or the reversing sleeve arrangement shown in 5 Patent 1,473,046, issued November 6, 1923 may be introduced between the distributor and the hub portion 31 to obtain reverse rotation at will.

The ports 25 are illustrated as being so positioned and of such area that the motive fluid is admitted during each alternate substantially full quarter revolution of the rotor and permitted to exhaust during the intermediate quarter revolutions. It will 10 of course be evident that by varying the proportions and location of the ports the motive fluid may be admitted during only a part of the outgoing piston stroke and the admitted fluid permitted to expand for the 15 balance of the stroke. It will also be apparent that if the apparatus is to be used as an internal combustion engine operating on the four-cycle principle, the ports may be arranged as illustrated in Patent No. 1,324,408 20 issued to myself and L. F. Ragot.

If it is desired that the weight of the device be reduced the webs or flanges 42 which connect the annular rows of cylinders of the members 10 and 11 may be of skeleton form, 25 that is, apertures 43 may be formed therein between adjacent cylinders, and inside of the row of connecting members 16, and apertures or recesses 44 may be formed in the outer edges of the web outside of said connecting members.

In Figs. 3 and 4 there is illustrated a construction which is similar in many respects to that illustrated in Figs. 1 and 2, but with the parts so designed that the cylinders form 40 the rotor and the track is rigid with the stationary casing. In this construction the two circular disks 10^a and 11^a have the same arrangement of cylinders, pistons, rigid connections and rollers, as above described. 45 The outer track member 21^a is rigidly secured to the stationary casing 14^a. The inner track member 22^a is rigidly secured to or integral with the distributor 23^a. The disk member 10^a has a hub or boss portion 50 supported by ball bearings within a flange 51 on the casing, and the distributor has a flange 52 to rigidly connect it to the casing. The cylinder member 11^a has a hub or boss portion 53 supported by ball bearings within a boss 54 on the casing. The boss portion 53 may be extended to form the main shaft 40^a of the apparatus. The distributor is thus 55 stationary and extends into one end of the rotor in alignment with the drive shaft 40^a which is rigidly secured to or integral with

the rotor. The passages and ports may be substantially the same as those illustrated in Figs. 1 and 2, although due to the fact that the distributor is stationary the use of annular passages such as 30 and 32 of Fig. 2 is 60 not necessary. In this form I have shown a single passage 26^a with branch passages leading in opposite directions and serving the function of both the passages 26 and 28 of Fig. 1.

This arrangement of stationary distributor in a pocket in the rotor may be varied in any of the ways disclosed in Patent 1,324,408, particularly if the present invention is to be employed in a four stroke cycle engine.

The spacing means between the two disk members 10^a and 11^a are shown as sleeves 17^a on the bolts 16.

Having thus described my invention, what I claim as new and desire to secure by Letters Patent is:

1. In combination a pair of parallel cylinders extending radially from and axially spaced along an axis of rotation, pistons therein, connections between said pistons intermediate of their ends, a track encircling said axis and presenting inner and outer parallel non-circular track surfaces and means engaging said tracks for controlling the reciprocation of the piston during the relative rotation of said cylinders and said track about said axis.

2. In combination a pair of parallel cylinders extending radially from and axially spaced along an axis of rotation, a track encircling said axis and presenting inner and outer parallel non-circular surfaces, rigid connections between said cylinders and extending across between said surfaces, pistons in said cylinders, and members connecting said pistons and also extending between said surfaces and adapted to engage therewith to effect the reciprocation of the pistons during the relative rotation of said cylinders and said track about said axis.

3. In combination a pair of parallel cylinders extending radially from and axially spaced along an axis of rotation, two members presenting opposed spaced elliptical surfaces in the same plane between said cylinders, the major axis of the inner ellipse being shorter than the minor axis of the outer ellipse, a member rigidly connecting said cylinders and movable in a circular path between said ellipses, the diameter of the path being greater than the major axis of the inner ellipse and less than the minor axis of the outer ellipse, pistons within said cylinders, and connections between said pistons and engaging with said ellipses to effect the reciprocation of the pistons during the relative rotation of the cylinders and ellipses.

4. In combination two members spaced apart along an axis of rotation and each including a plurality of radially disposed cyl-

- inders, each cylinder in one member being parallel to a corresponding cylinder in the other member, an annular row of connecting and spacing devices from one member to the other, a pair of members presenting opposed elliptical surfaces, one inside of said row of devices and the other outside of it, pistons in said cylinders, and connections between said pistons and engaging with said ellipses.
10. 5. In combination two members spaced apart along an axis of rotation and each including a plurality of radially disposed cylinders, an annular row of connecting and spacing devices from one member to the other and disposed between successive cylinders, a pair of track members between said first mentioned members, one facing inwardly and encircling said devices and the other facing outwardly and encircled by said devices, pistons in said cylinders, and means connected to said pistons and engaging said tracks for effecting the reciprocation of the pistons during rotation of the track members.
15. 6. In combination two members spaced apart along an axis of rotation and each including a plurality of radially disposed cylinders, an annular row of connecting and spacing devices from one member to the other and disposed between successive cylinders, a pair of track members between said first mentioned members, one facing inwardly and encircling said devices and the other facing outwardly and encircled by said devices, pistons in said cylinders, and means connected to said pistons and engaging said tracks for effecting the reciprocation of the pistons during rotation of the track members, and a stationary casing enclosing said parts and independent of the connections between said track members.
20. 7. In combination a stator and a rotor, one including two members spaced apart along the axis of rotation and each including a plurality of radially disposed cylinders, and the other including a pair of track members presenting opposed parallel non-circular track faces, pistons in said cylinders and provided with rollers engaging said track surfaces, and a motive fluid distributer rigid with said track members.
25. 8. In combination a stator and a rotor, one including two members spaced apart along the axis of rotation and each including a plurality of radially disposed cylinders, and the other including a pair of track members presenting opposed parallel non-circular track faces, pistons in said cylinders and provided with means engaging said track surfaces, and a casing rigidly connected to and encircling said cylinders and forming a part of the stator.
30. 9. In combination a pair of parallel cylinders extending radially from and axially spaced along an axis of rotation, pistons therein, connections between said pistons intermediate of their ends, a rotatable track encircling said axis and presenting inner and outer parallel non-circular track surfaces and means engaging said tracks for effecting the reciprocation of the piston during the rotation of said track about said axis.
35. 10. In combination two members spaced apart along an axis of rotation and each including a plurality of radially disposed cylinders, an annular row of connecting and spacing devices from one member to the other and disposed between successive cylinders, a pair of rigidly connected rotatable track members between said first mentioned
- members, one facing inwardly and encircling said devices and the other facing outwardly and encircled by said devices, pistons in said cylinders, and means connected to said pistons and engaging said tracks for effecting the reciprocation of the pistons during rotation of the track members.
40. 11. In combination a stator including a casing and two sets of axially spaced radially disposed cylinders and a rotor including a pair of track members presenting opposed parallel non-circular track faces in the same radial plane between said sets of cylinders, and a motive fluid distributer rigid with said track members, said stator having pistons in the cylinders and parts connected to said pistons in engaging said track members.
45. 12. In combination two members spaced apart along an axis of rotation and each including a plurality of radially disposed cylinders, pistons therein, a centrally disposed motive fluid distributer, a pair of track members, one facing outwardly and the other facing inwardly between said first mentioned members, means engaging said track members for effecting reciprocation of said pistons and means rigidly connecting the last mentioned track member to one end of said distributer, the first mentioned track member being connected to said distributer intermediate of the ends of the latter.
50. 13. A device constructed, as set forth in claim #12, and in which there is a stationary casing independent of the connections between the track members and the distributer.
55. 14. In combination two members spaced apart along an axis of rotation and each including a plurality of radially disposed cylinders, pistons therein, a centrally disposed motive fluid distributer, a pair of track members between said first mentioned members and disposed in the same plane, one facing outwardly and the other facing inwardly, means engaging said track members for effecting reciprocation of said pistons.

tons a stationary casing and connections between the inwardly facing track member and the distributor.

15. A device constructed, as set forth in claim #14, in which the connections between the track member and the distributor include a part extending in an axial direction at the outer ends of one row of cylinders and thence radially alongside said cylinders.

10 16. A device, as set forth in claim #14, in which the stationary casing is in part formed integral with one of the first mentioned members.

15 17. In combination a combined shaft and motive fluid distributor, an outwardly facing track member rigid therewith and disposed intermediate of the ends thereof, a second track member in the same plane and encircling the first mentioned track member and having an inwardly facing track surface, means for connecting the second mentioned track member to said distributor adjacent to one end of the latter, two sets of radially disposed cylinders disposed upon 20 opposite sides of said track members, rigid connections between said sets of cylinders, pistons in said cylinders, and means connected to said pistons for engaging said track members.

18. A device as constructed in claim #17 in which there is a stationary casing rigidly connected with said cylinders.

19. In combination a stationary casing, a pair of rigidly connected non-circular track members disposed in the same plane and relatively mounted in said casing intermediate of the ends thereof, a pair of cylinder members on opposite sides of said track members, and means extending between said track members and rigidly connecting said cylinder members.

20. In combination a casing, an annular row of radially disposed cylinders integral therewith, said casing having a hub portion provided with annular passages therein, a motive fluid distributor rotatably mounted in said casing and having passages communicating with said first mentioned passages and having ports for communication with said cylinders, pistons in said cylinders, a track rigidly connected to said distributor and rotatable therewith, and means engaging said pistons and said track for reciprocating the pistons during the rotation of the track.

Signed at New York in the county of New York and State of New York this 27th day of January, A. D. 1923.

CHAS. L. RAGOT.
